FEED WATER REGULATOR

Filed May 17, 1916

Fig. 1.

Patented Aug. 14, 1923.

1,464,669

UNITED STATES PATENT OFFICE.

GEORGE W. STETSON, OF HINGHAM, MASSACHUSETTS.

FEED-WATER REGULATOR.

Application filed May 17, 1916. Serial No. 98,029.

To all whom it may concern:

Be it known that I, GEORGE W. STETSON, a citizen of the United States, residing at Hingham, in the county of Plymouth and 5 State of Massachusetts, have invented certain new and useful Improvements in Feed-Water Regulators; and I do hereby declare the following to be a full, clear, and exact 10 description of the invention such as will enable others skilled in the art to which it appertains to make and use the same.

The present invention relates to feed water regulators, and more particularly to regulators employed in connection with 15 steam boilers.

It will be obvious to those skilled in the art that in cases where the steam demand upon the boiler and also the steam pressure are constantly varying, it is difficult to provide 20 a feed water regulator which will maintain a water input varying substantially in accordance with the steam output. Furthermore, regulators of this type must be capable of operating for long periods with comparatively 25 little attention and without liability of unexpected failure.

The object of the present invention is to provide a feed water regulator of simple and compact construction which operates efficiently 30 to supply water according to the varying requirements of the boiler.

With this object in view the several features of the invention consist in certain novel features of construction, combinations 35 and arrangements of parts hereinafter described and claimed, the advantages of which will be obvious to those skilled in the art from the following description.

In the accompanying drawings illustrating 40 the preferred form of the invention, Figure 1 represents an elevation of the regulator with the enclosing casing cut away to illustrate clearly the working parts; and Fig. 2 is a detail illustrating the improved form of 45 piston valve sleeve employed.

In the illustrated embodiment of the invention a float casing is formed by upper and lower flanged sections denoted, respectively, by 5 and 6, and secured by threaded 50 members 7. This casing is normally secured to the side of the boiler or housing at the proper height and is connected with the boiler by a steam connection 9 and water connection 10, which cause the level of water 55 in the casing to stand at the level of the water in the boiler. The interior of the cas-

ing may be conveniently designated as a "float chamber" and is provided with the usual threaded connections 11 and 12 for a water glass or other device for indicating 60 the height of the water in the chamber. A horizontal float lever 15 is fulcrumed in proximity to one end upon a short vertical link 16 which is pivoted at its lower end in ears 17 projecting from the guide casting 65 which is attached to the lower portion 6 of the casing. The float lever 15 supports a float 19 upon one end and is pivotally connected at its opposite end to the upper end of a valve stem 20. In the illustrated embodiment of the invention the float 15 is provided with a yoke 21 secured to the end of the lever and embracing the link 16 and valve stem 20. The valve stem is slidingly supported in an upper guide 23 and a lower 70 guide 24. A plurality of valve members 25 are mounted upon the lower portion of the stem and co-operate with valve sleeves 26 to control the passage of water from the chamber 28 into the chamber 29 formed in a valve 75 casing 27 which is secured to the underside of the float casing. The chamber 28 communicates directly with the usual feed pump and the chamber 29 is in constant communication with the interior of the boiler so 80 that, when the valves are opened, water is fed to the boiler by the pump. With this construction it will be obvious that as the level in the float chamber rises, the float is lifted therewith gradually depressing the 85 valve stem 20 and closing the valves. On the other hand, as the level in the float chamber drops, the weight of the float and lever cause a like movement of the float, gradually elevating the valve stem and opening the 90 valves. In the illustrated embodiment of the invention the effective length of the moment arm between the center of mass of the float 19 and lever 15 and the fulcrum formed by the link 16, and the moment arm 95 between the fulcrum and the connection with the valve stem 20 is as fifteen to one, thus causing the float to exert a powerful leverage tending to move the valve stem. In order to secure the full buoyancy of the float for 100 moving the valve stem, means are conveniently provided for counterbalancing the weight of the float lever and the connecting parts. To this end a plurality of separable counterweights 30 are mounted on 105 the upper end of the valve stem and supported by a flanged collar 31 secured to the

valve stem. In order to facilitate the addition to or removal of counterweights from the valve stem a flanged cover plate 33 is detachably connected to the upper section 5 of the casing by threaded members 35. It is obvious that in a device of this character the connections between the float and operating valves should be simple and compact and free from stuffing boxes or other like constructions which would tend to impede the movements of the valves. In the present mechanism the float lever is connected directly to the valve stem which is slidingly supported in upper and lower bearings which serve to guide the stem without substantially impeding the movements. It will be noted from an inspection of the drawings that the upper guide comprises a sleeve 37 which is threaded in the lower portion of the casing and receives the valve stem, this portion of which is provided with a series of concentrically arranged rings 38 which permit the valve stem to move freely through the guide but prevent any considerable flow of water from the float chamber to the intake chamber or vice versa. The water valve is balanced and comprises two opposed piston valves mounted upon the valve stem and freely movable in the valve sleeves 26, each of which consists of a tubular cage 40, threaded in an opening formed in a flanged portion of the casing and provided with a series of uniformly arranged ports 41. Each piston valve is loosely received in the valve sleeve and the vertical movement of the valve stem causes the ports to be uncovered more or less to control the supply of water. As the piston valve controls the supply of water through the vertical movement and is not intended to completely cut off communication between the two chambers it will be obvious that it may fit loosely in the valve cage and thus avoid the liability of jamming or sticking. When the boiler is constantly supplying steam at normal rating the water level is higher than otherwise, and as the demands upon the boiler increase, the level of water tends to drop, which causes the admission of more water. In order to cause the valve to supply the necessary volumes of water to the boiler through the proper range in levels the ports 41 are triangular in shape and arranged to deliver a progressively increasing supply of water to the boiler as the valve stem is elevated, owing to a lower water level. This type of port serves to supply the increased volume of water necessitated by a heavy expenditure of steam without causing the valve to fluctuate from a completely open to a closed position, first supplying too much and then too little water. It is desirable under certain conditions to provide an internal mechanism for opening the water valves independently of the position of the float, as

in cases when the boiler is to be put under a hydrostatic pressure. To this end a lifting rod 42 is threaded in a plug 43 secured in the lower portion of the valve casing and is arranged to engage with the lower end of the valve rod to open the valves and permit the flow of water into the boiler. The lifting rod is provided with any usual type of stuffing box, indicated at 45.

It is desirable that if the water level in the boiler for any reason whatsoever rises or falls beyond certain predetermined limits, an alarm shall be given. In the present invention a steam whistle is secured to the float casing and is controlled by a normally closed valve which may be operated at predetermined levels of the water by connections between the valve and float lever. Any usual type of steam whistle, indicated at 50, is secured to the upper portion of the float casing and is provided with a controlling valve consisting of a conical valve seat 51 and a cooperating needle valve 52 which serves to normally prevent steam from the float chamber from entering the whistle. The needle valve is secured upon the free end of an arm 55 fulcrumed at 56 and having an oppositely extending arm 57 secured thereto which is adapted to be actuated under certain conditions to depress the needle 52 and open the controlling valve. In order to cause the operation of the arm 57 at predetermined levels, an inclined arm 58 is secured to the float lever 15, as shown clearly in the drawings, and is provided with a substantially horizontal platform 60 at its upper end which is positioned above the fulcrum about which the float lever turns. The arm 57 is provided with members 61 and 62 which are arranged to engage with opposite sides of the platform 60 when the latter is tipped sufficiently to cause either side to be raised to a predetermined height. It will be obvious that if the water level drops below a predetermined height the platform 60 will engage with the lower end of the member 61 to open the controlling valve, and that if the water level rises above a predetermined height the platform will be tipped in the opposite direction to engage with the member 62 and open the controlling valve. This forms an extremely simple and efficient mechanism for operating the whistle or alarm when the water level exceeds certain predetermined limits. The members 61 and 62 are conveniently threaded in the arm 57 to enable high and low limits of water level to be varied as desired. The controlling valve is normally maintained in a closed position by a counterweight 63 which is supported upon the arm 57, as shown clearly in the drawings.

Difficulty has been experienced heretofore in properly securing the float to the end of the float lever as the float must be harne- 120

cally sealed and remain sealed when subjected to severe working conditions. In the present invention a seamless substantially spherical float is provided and is supported 5 in a basket secured to the end of the float lever. This basket consists of a pair of straps 70 and 71 arranged to form loops passing about the float at right angles and secured at their free ends to a collar 72 10 threaded upon the end of the float lever. The straps clamp the float firmly against the face of a curved head 73 secured to the end of the float lever, as shown clearly in the drawings. With this construction the float is 15 positioned in the basket and by threading the collar in the proper direction on the float lever the straps are caused to clamp the float firmly against the head 73. The collar may be conveniently locked in any adjusted 20 position by a locking nut 75 threadedly mounted upon the lever. With this construction the float is firmly clamped to the end of the lever without the necessity of piercing or damaging the float in any way 25 which would tend to cause leakage.

It will be obvious that a float employed in this manner is subjected to a considerable external pressure which is constantly varied, and although these floats are tested for an 30 external pressure greater than the normal steam pressure of the boiler, the constant flexing of the float, due to variation in the unbalanced external pressure, weakens the float and very materially impairs the efficiency. In order to balance the pressure 35 within and without the float it is customary to add a measured quantity of water depending upon the maximum external pressure and temperature to which the float is subjected and which is vaporized to create an 40 internal pressure equal to the external pressure upon the float. This expedient for balancing the pressure is not satisfactory, however, as it is found that, owing to the continuous condensation of steam in the float 45 chamber and leakage of cold water from the valve chamber, the temperature of the water in the lower portion of the chamber is less than the normal boiling point of the water 50 at the pressure in the chamber. Thus, if water is employed the pressure within the float, which is substantially equal to that due to the mean temperature within the float 55 chamber, is consequently less than the pressure without the float. In the present invention the external and internal pressures upon the float are balanced by inserting in the float a measured quantity of liquid which 60 has a boiling point lower than the boiling point of water at any given pressure. With this arrangement the mean temperature in the float chamber, which is lower than the boiling point of water at the corresponding 65 pressure, will serve to vaporize the liquid within the float and produce an internal

pressure substantially equal to the external pressure. In the illustrated embodiment of the invention ethyl chloride, sulphuric ether, alcohol and benzine may be mentioned as some of the liquids having the desired characteristics. 70

While it is preferred to employ the specific construction and arrangement of parts shown and described, it will be understood that this construction and arrangement is 75 not essential except so far as specified in the claims, and may be changed or modified without departing from the broader features of the invention.

The invention having been described, what 80 is claimed is:

1. A feed water regulator, having, in combination, a substantially horizontal float lever fulcrumed adjacent one end, a float supported upon the end of the lever, a vertical 85 valve stem connected with the opposite end of the lever adjacent the fulcrum, valve sleeves having a plurality of triangular ports formed therein, and a piston valve secured to the valve stem and arranged to control 90 the flow of water through the valve ports as the stem is moved vertically.

2. A feed water regulator, having, in combination, a float lever fulcrumed adjacent one end, a float supported upon one end of 95 the lever, a vertically movable valve stem connected to the opposite end of the lever adjacent the fulcrum, upper and lower guide members for the valve stem, a counterweight for the float and lever, a piston valve mounted upon the stem between the guide members, and a valve sleeve co-operating with the piston valve to control the flow of water. 100

3. A feed water regulator, comprising a casing having a float chamber therein, a float lever pivoted in the casing, a float supported upon one end of the lever, a high and low water alarm, and connections between the float lever and alarm including a normally horizontal platform for causing the operation of the alarm when the water level in the chamber exceeds predetermined limits. 105

4. A feed water regulator, comprising a casing having a float chamber contained therein, a float lever pivoted in the casing, 115 a float supported upon one end of the lever, an alarm device, an operating arm for the alarm, a normally horizontal platform supported by the float lever, and connections between the platform and operating arm for permitting the actuation of the alarm device 120 when the platform is tipped by the float lever.

5. A feed water regulator, comprising a 125 casing having a float chamber contained therein, a normally horizontal float lever pivoted in the casing, a float supported upon one end of the lever, an arm secured to the float lever, a platform supported upon the arm above the fulcrum for the lever, an 130

- alarm device, and connections between the alarm device and platform for permitting the operation of the alarm device when the platform is moved beyond predetermined limits by the movement of the float lever.
6. A feed water regulator for steam boilers, comprising a casing having a float chamber contained therein, a float lever pivoted in the casing, a float supported upon one end of the lever, a whistle secured to the casing and adapted to be operated by the steam pressure within the casing, a valve normally closing the whistle, an arm supporting the valve, means acting on the arm to normally maintain the valve closed, and connections between the float lever and arm including a normally horizontal platform for operating the arm when the water level exceeds predetermined limits.
- 20 7. A feed water regulator, comprising a casing having a float chamber contained therein, a float lever supported in the casing, a float, a curved float supporting head secured to the end of the lever, a collar threaded upon the lever behind the head, a plurality of straps looped about the float and secured at their free ends to the collar to clamp the float against the face of the head, and a locking nut threaded upon the lever to lock the collar in adjusted position.
- 25 8. A water level apparatus for steam boilers, comprising a casing having a float chamber contained therein and adapted to be connected with the steam and water spaces in the boiler, and a sealed float supported in the casing and containing a liquid, the boiling point of which is lower than the boiling point of water at any given pressure.
9. A water level apparatus for steam boilers, comprising a casing having a float chamber contained therein and adapted to be connected with the steam and water spaces in the boiler, and a sealed float supported in the casing and containing a predetermined quantity of alcohol which has a lower boiling point than water at any given pressure.
- 10 10. A feed water regulator having, in combination, a float chamber adapted to be connected with the steam and water spaces of a boiler, a float lever fulcrumed within the chamber, a valve-casing having a partition-wall separating it into inlet and discharge chambers and provided with a threaded opening therein, an apertured valve-sleeve threaded in the opening and having the apertures located wholly at one side of the partition, a valve-stem connected with the float lever, and a piston-valve mounted upon the stem and sliding within the valve-sleeve to control the flow of water from the inlet to the discharge chamber.
- 15 11. A feed water regulator having, in combination, a float chamber adapted to be connected with the steam and water spaces of a boiler, a float lever fulcrumed within the chamber, a float supported upon one end of the lever, a valve rod connected adjacent the opposite end of the lever, valve sleeves having substantially triangular ports formed therein, and balanced piston valves mounted upon the valve rod and each co-operating with a sleeve to feed a variable supply of water to the boiler in accordance with the position of the float.

GEORGE W. STETSON.
